UNITED STATES PATENT OFFICE.

KARL K. NIELSEN, OF CHICAGO, ILLINOIS, ASSIGNOR TO ALCOR MANUFACTURING COMPANY, OF CHICAGO, ILLINOIS, A CORPORATION OF ILLINOIS.

CANDLE SOCKET.

Original application filed January 28, 1927, Serial No. 164,165. Divided and this application filed August 8, 1927. Serial No. 211,320.

My invention relates to lighting fixtures of the candle type, in which a socket for the lamp is supported in the upper end of a tubular jacket by a support connected to the fixtures at or near the lower end of this jacket, and in which the shell of the socket is insulated from this jacket by a tube of insulating material.

Generally speaking, my invention aims to provide a so-called candle-socket for this purpose which can readily be adjusted as to its length, which will permit the needed adjustment in length to be made accurately without the use of a rule, in which a single and accessibly positioned screw locks the adjustably connected parts against displacement, and in which cheaply manufactured parts can be employed for insulating and supporting the socket, and in which numerous constituent elements interlock with each other to prevent their relative rotation. It also aims to provide means for supporting an insulating tube housing the conducting parts of the socket, and auxiliary means for frictionally holding this tube in position.

More particularly, my invention provides a socket support for an electric appliance of this kind in which the main members consist of two slidably interfitting forked members, in which graduations on one of these members indicate the effective total length of the appliance; and in which simple formations on the arms of the two forks co-operate with a single screw and a presser member in holding the two forked members rigidly connected, and in preventing the fork arms from bending toward each other.

Furthermore, my invention provides a construction of this general nature in which integral formations on one of the forked members suffice as supports for supporting the insulating tube and in which one of the insulations for the conducting parts of the socket is formed for retaining this tube on the said formations.

Still further and more detailed objects will appear from the following specification and from the accompanying drawings, in which

Fig. 1 is a central, vertical and longitudinal section through a candle socket embodying my invention, showing this in connection with the lamp and the usual adjacent fixture portions.

Fig. 2 is an enlarged central, vertical and

longitudinal section taken through the insulating tube of Fig. 1 and through the upper portion of the support in a plane at right angles to Fig. 1, with the socket proper shown in elevation.

Fig. 3 is a perspective view of the upper forked member.

Fig. 4 is a horizontal section taken along the line 4—4 of Fig. 2 and looking upward.

Fig. 5 is a perspective view of the upper end portions of the lower forked member of the support and of the presser member which bears against one arm of this forked member.

Fig. 6 is a side elevation of a lower portion of the upper forked member, with one arm end of the lower forked member shown in position for interlocking with the same.

Fig. 7 is a plan view of the intermediate one of the three insulating disks disposed below the metal socket shell, drawn on the same scale as Fig. 1.

Fig. 8 is a plan view of the lowest insulating disk.

Fig. 9 is a plan view of the upper insulating disk.

This application is a division of application Serial Number 164,165 filed Jan. 28, 1927 now Patent Number 1,690,693, dated Nov. 6, 1928.

In the illustrated embodiment, the support for the socket proper comprises two forked members each of which has vertical shanks spaced by an adequate distance for affording stiffness to the resulting structure. The lower of these forked members comprises a base 1 threaded to fit a threaded stud 2 at the upper end of the fixture 3 to which my candle socket is attached, and a pair of riser shanks 4. Each of these shanks bears flatwise against one of the shanks 7 of the upper forked member, and the lower shanks 4 have lateral flanges 5 snugly housed by lateral flanges 6 on the shanks 7 of the upper forked member, whereby these flanges prevent relative lateral and rotational movement of the two forked members.

The shanks 7 of the upper forked member are connected at their upper ends by a top plate 8 having a perforation 9 larger in diameter than the shank 10 of a rivet 11 which effectively secures the threaded metal socket shell 12 to the said top plate. To insulate this metal socket shell from the top plate I provide four insulators through which the

said rivet shank 10 extends, one being an inner insulator 13 which seats on the bottom of the said threaded shell and which supports a radial arm 14 of one wire terminal 15 of the socket. The rivet shank 10 extends through this radial arm 14 also and has its upper head 10^A disposed for engaging the axial terminal 16 of a lamp 37 screwed into the socket shell 12.

10 An upper insulating disk 17 interposed between the top plate 8 and the base of the metal socket shell 12 has a central perforation through which the rivet shank 10 extends and also has two opposite peripheral notches 15 through which the wire terminals 15 and 18 respectively extend, the terminal 18 being riveted to the said socket shell. These wire terminals also extend through opposed edge recesses 19^A in an intermediate insulating 20 disk 19 which has a perforation 19^B formed with enlargements for receiving the flanges of the upper forked member. The lowermost insulator 20 has a central portion underhanging the top plate 8 of the upper forked member and has opposed recesses 20^A laterally housing the flanges 6 on that forked member, and this lowermost insulator also has opposed edge recesses 20^B through which the wire terminals 15 and 18 respectively extend.

25 With the parts thus arranged, the recesses engaged by the shanks of the upper forked member prevent all three of the insulators below the top plate 8 of that member from rotating about the rivet shank 10, and the engagement of other recesses by the wire terminal 18 (which is secured to the threaded socket shell) prevents that shell from rotating. Hence the fastening of the single rivet (which has its lower head 10^B underhanging 30 the lowermost insulator 20) secures the socket proper rigidly to the upper forked member.

Extending loosely through a perforation near the upper end of one shank 4 of the lower forked member is a screw 21 which has its tip adapted to enter a recess 32 in the opposite shank 4, and which screw extends through vertical slots 7^A in both shanks of the upper supporting member. The head of the screw 21 engages the outer face of the shank 4 which is perforated for the screw and the screw is threaded through a presser plate 22 which engages the inner face of the shank 7, which presser plate has flanges 22^A at its ends for overhanging the flanges 7^A on the last named shank. The tip portion of the shank 4 which has the said recess 32 has as a rigid extension a T-shaped part including a stem 23 which extends through the slot 7^A in the adjacent lower shank 7 and 45 a head 24 which bears against the inner face of the last named shank. With the screw 21 of a suitable length, a tightening of this screw simultaneously clamps the shanks 4 and 7 of the two forked members (at the right side of Fig. 2) between the presser member

and the head of this screw, and also causes the tip of the screw to press the opposite lower shank 4 outwardly so as to force the said head 24 against the inner face of the upper shank 7 at the left side of Fig. 2. Consequently, 70 the single screw simultaneously clamps each shank of the lower forked member to the adjacent shank of the upper forked member, so that I secure an unusually rigid assembly.

However, a slight loosening of the screw 75 21 releases this clamping and permits the upper forked member to be slid freely upward or downward to vary the effective length of the socket. To facilitate an exact adjustment of this length without requiring 80 the use of a scale, I preferably mark one shank of the upper forked member with graduations 85 25 adapted to be read from the upper end of the adjacent shank of the lower forked member.

When installed, the supporting structure is usually concealed by a white or ivory tinted tube 26 supported by a suitable cup-like structure—such as that shown in Fig. 1—which forms no part of my present invention. This 90 tube 26 may be of glass and I desirably cushion it from jarring against the metal screw shell 12 of the socket by interposing an insulating tube 27 of fibre or the like. To support this tube 27, I form each shank 7 of the 95 upper forked member with an outwardly directed finger 28, so that the tube 27 seats on these fingers. Then I provide nubs 29 on the periphery of the insulator 17 on which the metal screw shell seats, which nubs project so as to fit the insulating tube 27 with sufficient friction to hold the said tube down on the fingers 28.

Since both forked members as well as all 105 of the four insulators and the presser plate are easily made by simple punch press operations followed by only two threading operations, the construction of my adjustable socket-supporting and socket-insulating structure is both simple and inexpensive. 110 Moreover, the assembly is also easy, as the T-shaped extension on one shank of the lower forked member can readily be interlocked with a slotted shank of the upper forked member while these two members are relatively tilted, as shown in Fig. 6.

However, I do not wish to be limited to the 115 details of the construction and arrangement above described, since changes might obviously be made without departing either from the spirit of my invention or from the appended claims. Nor do I wish to be limited to the use of all novel features of my invention in combination with one another.

I claim as my invention:

1. A support for an upright lamp socket, comprising an upper member of inverted U-shape secured at its top to the socket; a lower U-shaped member adapted to be secured to a fixture part and having its shanks 120 130

slidably engaging the shanks of the upper member, the shanks of the upper member being provided with longitudinal slots; and means spanning the shanks of the lower member and extending through the slots in both shanks of the upper member and operating in the same direction for clamping the two shank tips of the lower member respectively against the inner and the outer faces of the shanks of the upper member.

2. A support for an upright lamp socket, comprising an upper member of inverted U-shape secured at its top to the socket; a lower U-shaped member adapted to be secured to a fixture part and having its shanks slidably engaging the outer faces of the shanks of the upper member, the shanks of the upper member being provided with longitudinal slots and a presser member engaging the inner face of one shank of the lower member; a screw threaded through the presser member and extending through the slots in both shanks of the upper member for clamping the shanks of the lower member respectively against those sides of the respectively adjacent shanks of the upper member which face in the same direction.

3. A socket and support as per claim 1, in which a shank of the lower member has portions thereof respectively engaging the inner and the outer faces of the adjacent shank of the upper member, thereby cooperating with the said means for rigidly spacing the shanks of each member.

35 4. A socket support comprising an upper member of inverted U-shape secured at its top to the socket and having its shanks provided with longitudinal slots; a lower U-shaped member having its shanks slidably engaging the outer faces of the shanks of the upper member; an anchoring element fast on one shank of the lower member engaging the inner face of the adjacent shank of the upper member, and means including a clamping member extend-

ing through the two shanks at the other side of the support from the anchoring element for clamping the last named two shanks to each other and for rigidly spacing the shanks of the lower member from each other.

5. A socket support as per claim 4, in which the anchoring element comprises a substantially T-shaped extension of the shank on which it is fast, the stem of the T being narrower than the slot in the adjacent shank of the upper member and the said extension being formed to permit of inserting the head of the T through the said slot when the two members are in a relatively oblique position.

6. A socket support comprising an upper member of inverted U-shape secured at its top to the socket and having its shanks provided with longitudinal slots; a lower U-shaped member having its shanks slidably engaging the outer faces of the shanks of the upper member, an anchoring element fast on one shank of the lower member engaging the inner face of the adjacent shank of the upper member, a presser member engaging the inner face of the shank of the lower member at the opposite side of the support from the anchoring element, and a screw threaded through the presser member and having a head engaging the outer face of the last named shank of the lower member, the screw having its tip engaging the inner face of the shank of the lower member adjacent to the anchoring element.

7. A socket and support combination as per claim 1, in combination with fingers projecting in opposite directions from the upper member, an insulating tube supported by the said fingers and housing the socket, and an insulator disposed between the top of the upper member and the socket, the insulator having radially projecting nubs engaging the bore of the insulating tube.

Signed at Chicago, Illinois, August 4, 1927.
